US00D732359S

(12) **United States Design Patent**
Ericksen et al.

(10) **Patent No.:** US D732,359 S
(45) **Date of Patent:** ** Jun. 23, 2015

(54) **CONDUIT REMOVAL TOOL**

(75) Inventors: **Kent C. Ericksen**, Centerville, UT (US);
Tres Wangsgaard, Holladay, UT (US);
Stuart Eyring, Bountiful, UT (US);
Stephanie L. Hunter, Farmington, UT (US)

(73) Assignee: **Orbit Irrigation Products, Inc.**, North Salt Lake, UT (US)

(**) Term: **14 Years**

(21) Appl. No.: **29/430,121**

(22) Filed: **Aug. 21, 2012**

(51) LOC (10) Cl. **08-05**

(52) U.S. Cl.

USPC **D8/14**

(58) **Field of Classification Search**

USPC D8/14, 25, 29, 33, 34, 40, 307, 349,
D8/354, 397; 81/3.4, 60, 63.1, 63.2;

(57) **CLAIM**

The ornamental design for a conduit removal tool, as shown and described.

DESCRIPTION

FIG. 1 is a first perspective view of one embodiment of a conduit removal tool according to our new design;

FIG. 2 is a second perspective view of the embodiment of the conduit removal tool shown in FIG. 1;

FIG. 3 is a rear view of the embodiment of the conduit removal tool shown in FIG. 1;

FIG. 4 is a top view of the embodiment of the conduit removal tool shown in FIG. 1;

FIG. 5 is a front view of the embodiment of the conduit removal tool shown in FIG. 1;

FIG. 6 is a first side view of the embodiment of the conduit removal tool shown in FIG. 1;

FIG. 7 is a second side view of the embodiment of the conduit removal tool shown in FIG. 1;

FIG. 8 is a bottom view of the embodiment of the conduit removal tool shown in FIG. 1;

FIG. 9 is an enlarged view of area 9 shown in FIG. 5;

FIG. 10 is a first perspective view of a second embodiment of a conduit removal tool according to our new design;

FIG. 11 is a second perspective view of the embodiment of the conduit removal tool shown in FIG. 10;

FIG. 12 is a rear view of the embodiment of the conduit removal tool shown in FIG. 10;

FIG. 13 is a top view of the embodiment of the conduit removal tool shown in FIG. 10;

FIG. 14 is a front view of the embodiment of the conduit removal tool shown in FIG. 10;

FIG. 15 is a first side view of the embodiment of the conduit removal tool shown in FIG. 10;

FIG. 16 is a second side view of the embodiment of the conduit removal tool shown in FIG. 10;

FIG. 17 is a bottom view of the embodiment of the conduit removal tool shown in FIG. 10; and,

FIG. 18 is an enlarged view of area 18 shown in FIG. 14. The portions of the conduit removal tool shown in broken lines are for the purpose of illustrating unclaimed portions of the article and form no part of the claimed design.

1 Claim, 6 Drawing Sheets
